UNITED STATES PATENT OFFICE

147,039

DESIGN FOR A MINIATURE RACING CAR

Orville Z. Frazier, Elkhart, Ind., assignor of one-half to R. J. St. Louis, Detroit, Mich.

Application April 5, 1946, Serial No. 128,311

Term of patent 7 years

(Cl. D34—15)

To all whom it may concern:

Be it known that I, Orville Z. Frazier, a citizen of the United States, residing at Elkhart, Indiana, have invented a new, original, and ornamental Design for Miniature Racing Car, of which the following is a specification, reference being had to the accompanying drawing, forming part thereof, wherein:

Fig. 1 is a top plan view of a miniature racing car showing my new design.

Fig. 2 is a side view thereof.

Fig. 3 is a front view of the same.

Fig. 4 is a rear view.

I claim:

The ornamental design for a miniature racing car, as shown.

ORVILLE Z. FRAZIER.
